CONTROL PLATE FOR MAGNETIC RECORDING AND REPRODUCING MACHINE

Robert C. Zimmerman, Chicago, Ill., assignor to Bell & Howell Company, Chicago, Ill., a corporation of Illinois

Filed Apr. 7, 1964, Ser. No. 79,386

Term of patent 14 years

(Cl. D26—14)

Fig. 1

Fig. 2

FIGURE 1 is a top front perspective view of a control plate for magnetic recording and reproducing machine showing my new design; and

FIGURE 2 is a top rear perspective view thereof.

The bottom of the control plate is substantially plain and unornamented.

I claim:

The ornamental design for a control plate for magnetic recording and reproducing machine, as shown.
